DREDGE BUCKET

William H. Taylor, Phillipsburg, N. J., assignor to
 Taylor-Wharton Iron & Steel Company, High
 Bridge, N. J., a corporation of New Jersey

Application December 18, 1934, Serial No. 758,113

4 Claims. (Cl. 37—191)

My invention relates to endless conveyers of the elevator and chain dredge type and provides certain improvements in connection therewith.

In U. S. Letters Patent No. 1,962,075, granted June 5th, 1934, on the application of Gerald Hillsdon Hutton, there is disclosed means to obviate spilling and loss of material from the buckets during elevating and dumping operations, said means comprising an auxiliary lip in the form of a shallow trough-shape pan open at both ends, pivotally mounted on the back wall of one bucket and having sliding engagement with the front wall of the next adjacent bucket so as to span or close the gap between the buckets.

The device of the patent, in principle and substance, is highly meritorious but suffers the objection and disadvantage that it makes for foundry problems and difficulties, frequently resulting in wastes; in service, the assembly presents pockets in the slide area liable to trap material and so interfere with the efficient operation of the pans even to the point of breakage or deformation of the connecting parts; and, finally the matter of repair or replacement is a serious problem.

The object of the invention is to improve upon the construction and assembly of the device of the patent so that there will be no foundry difficulties, and so that there will be no blind cavities in the nature of culs-de-sac or pockets for the trapping of material, and so that the matter of repair or replacement is reduced to a very simple proposition.

The nature, characteristic features, and scope of the invention more readily will be understood from the following description, taken in connection with the accompanying drawing, forming a part hereof, wherein:

Figure 1 shows in sectional elevation, part of a chain of buckets embodying my improvements;

Fig. 2 is a section on line 2—2 of Fig. 1;

Fig. 3 is a section on line 3—3 of Fig. 1; and

Fig. 4 is a detail of the pintle or pivotal mounting for the pan.

In Fig. 1, there is illustrated a chain of buckets having the Hutton servapan or non-spill element bridging the interbucket space and flexibly joined to two adjacent buckets for coordinate operation therewith. The buckets 5, generally

speaking, may be of the conventional type pivotally joined as at 6. The auxiliary lip or servapan is generally indicated at 7 and in accordance with the Hutton practice, it is pivotally mounted on the back wall of one bucket and in slidable engagement with the front wall of the next adjacent bucket.

The pivotal connection of the auxiliary lip is accomplished through the agency of a pintle or pivot pin 8 in cooperation with hollow engaging

portions of the bucket and lip, the pin being held against turning movement by T-head 9 lodged in a complementary socket and secured against casual displacement by a cotter pin 10.

The body of the auxiliary lip or pan is arched transversely and also in the direction of its length so as closely to follow the contour of the bucket with which it has sliding connection and its generally trough or pan shape is defined by outwardly flaring side walls 11. The latter are formed with outwardly divergent lugs 12 terminating in apertured brackets 13 which constitute supports or carriers for demountable shoes 14 rigidly secured to the carriers as by bolts 15. The shoes have clips 16 which bear against the end wall of the brackets and the shoes are inturned or directed towards each other and they provide the sliding connection for the pan by their cooperation with rails 17 on the complementary bucket. The rails 17 flank the breast of the bucket and being outwardly directed, there is no excess clearance between the pan and the bucket such as may be calculated to trap spoil and result in distortion or breakage of parts.

Having described the invention, I claim:—

1. In a bucket line, a pair of buckets, a pan pivotally mounted on the near edge of one bucket and shaped for close contour fit with the breast of the other bucket and having brackets, rails on the other bucket within the span of the brackets, and shoes removably mounted on the brackets and extending inwardly for lapping engagement with the rails to admit of sliding movement of the pan.

2. In a bucket line, a pair of buckets, a trapping lip flexibly connecting them, one of said buckets having laterally directed ribs constituting rails, and the lip having rearwardly extending brackets with replaceable shoes for sliding engagement with the rails.

3. In a bucket line, a pair of buckets, a trapping lip adapted to span the interbucket space and pivotally mounted in the mouth of one bucket, and slidably engaging laterally extended rails on the other bucket through the medium of brackets mounted on the lip in flanking relation with the rails, and shoes demountably carried by the brackets and directed inwardly in lapping engagement with the rails.

4. In a bucket line, a pair of buckets, a trapping member flexibly connecting them, one of said buckets having laterally directed offsets providing outside rails, the trapping member having lugs extending laterally beyond the rails, and demountable shoes carried by the lugs adapted and arranged for sliding connection with the rails.

WILLIAM H. TAYLOR.
